Primary Examiner — Mark Goodwin(74) *Attorney, Agent, or Firm* — Waddey & Patterson, P.C.; Lucian Wayne Beavers(57) **CLAIM**

The ornamental design for a body panels and cab assembly for a road construction machine, as shown and described.

DESCRIPTION

FIG. 1 is a left front perspective view of the body panels and cab assembly for a road construction machine showing our new design.

FIG. 2 is a right rear perspective view thereof.

FIG. 3 is a right front perspective view thereof.

FIG. 4 is a left rear perspective view thereof.

FIG. 5 is a right side elevation view thereof.

FIG. 6 is a left side elevation view thereof; and,

FIG. 7 is a front elevation view thereof.

The broken lines are shown for environmental purposes only and form no part of the claimed design.
